EUGENE C. HERTHEL, OF CHICAGO, ILLINOIS, ASSIGNOR TO SINCLAIR REFINING COMPANY, OF NEW YORK, N. Y., A CORPORATION OF MAINE

OPERATION OF PRESSURE STILLS

Original application filed November 21, 1924, Serial No. 751,213. Divided and this application filed February 27, 1928. Serial No. 257,353.

This invention relates to improvements in the cracking of heavier hydrocarbon oils, such as gas oil, for the production of lighter hydrocarbon oils, such as gasoline and pressure 5 distillate, therefrom. The invention includes improvements in the operation of pressure cracking stills, particularly circulatory pressure stills, and improvements in the operation of reflux towers employed in 10 conjunction with pressure cracking stills. This application is a division of my copending application Serial No. 751,213, filed November 21, 1924.

When heavy hydrocarbons are distilled 15 under pressure, they are "cracked" with the production of lighter oils. The products of the cracking reaction also include incondensable gases, and carbon or coke, or heavy tar. In the commercial operation of a pressure 20 still, some definite product or group of products, for example gasoline or pressure distillate, is usually desired but the vapors escaping from the still itself may include heavier constituents in addition to the constituents desired in the pressure distillate; and, in some cases, particularly in the distillation of lighter charging stocks, the escaping 25 vapors may include vaporized constituents from the charging stock in their original condition. The vapors from the pressure still are commonly subjected to a refluxing operation to effect, to a greater or less extent, the return of such heavier vaporized constituents 30 to the still for further treatment therein, but, as ordinarily practiced, such methods have nevertheless resulted in the production of distillates containing large amounts of constituents heavier than the desired pressure 35 distillate. For example, in treating gas oil for the production of gasoline by such methods, the pressure distillate usually includes a considerable amount of constituents of a kerosene character and others even heavier, so that it has been necessary to subject a relatively large amount of distillate to 40 redistillation to fractionate it into merchantable products and to separate the heavier components. Where refining methods involving chemical treatment followed by redistillation 45 have been applied to such distillates, this has

resulted in the chemical treatment of an amount of oil materially larger than that obtained as merchantable products.

According to the present invention, the pressure distillation is carried out to produce a more concentrated distillate of the desired character containing an increased amount of components suitable in the desired products and a decreased amount of heavier constituents. 55

According to the present invention, condensed pressure distillate, from the same still or from other stills, or a fraction including constituents of corresponding character, is employed for promoting and controlling in 60 an improved manner a refluxing operation to which the vapors from the pressure still are subjected and for returning to the pressure still the heavier constituents of the vapors unsuitable as components of the desired pressure distillate with resulting improvement in 65 the operation of the pressure still itself. Further, reflux from the refluxing operation, including such heavier constituents of the vapors, is positively subjected to the cracking 70 temperature before being permitted to again escape from the pressure still as a vapor. 75

When a charge of oil, such as gas oil, is subjected to a cracking temperature in a pressure still, cracking takes place in a gradual and progressive manner. Lighter constituents produced by the cracking operation are vaporized, and other constituents, such as heavier hydrocarbons formed by the cracking 80 operation, may remain and mix with the charge in the still. A small amount of asphaltic or pitch-like constituents is also progressively formed. During the early 85 part of the operation, these pitch-like constituents may remain more or less completely in solution in the charge, but with gradual and progressive cracking the amount of such constituents gradually and progressively increases until the amount of such constituents increases beyond the saturation point when 90 precipitation and deposition of these constituents begins unless steps are taken to prevent it. As the charge becomes supersaturated with the pitch-like constituents, they 95 tend to deposit upon the heating surfaces of 100

the still with consequent danger of overheating and failure of the heating surfaces if the still is not shut down at more or less frequent intervals for cleaning. Initially, 5 the entire charge of oil in the still acts as a solvent for the pitch-like constituents, but, as portions of the charge are cracked and vaporized, the solvent effect of the charge of oil decreases while the amount of pitch-like 10 constituents increases until finally deposition of pitch-like constituents occurs.

In a prior application filed July 12, 1922, Serial No. 574,380, there is described an improved process of cracking hydrocarbon oils 15 according to which the concentration of pitch-like constituents in the charge is controlled during the operation of the pressure still by withdrawing pitch-laden tar and introducing fresh charging stock at a regulated rate to maintain the pitch content of the 20 charge below the saturation point. In one aspect, the present invention involves a further improvement upon the process described in this prior application, and similarly 25 may involve carrying out the cracking operation with the introduction of fresh charging stock and the withdrawal of pitch-laden tar to maintain the pitch content of the charge below saturation.

30 According to the present invention, the vapors from the pressure still are subjected to a refluxing operation in direct contact with an oil including constituents corresponding in character to the desired pressure distillate. 35 This oil employed to promote the refluxing operation is more or less completely vaporized by contact with the vapors from the still and the cooling effect of the vaporization effects a sharp refluxing of the heavier vapors, 40 particularly of the constituents heavier than the vaporized constituents. In this way, by regulating the amount and character of the refluxing oil introduced into direct contact with the vapors from the still, a sharp fractionation 45 between the components suitable in the desired pressure distillate and the heavier components can be effected, and the character of the pressure distillate as well as of the refluxed constituents can be more or less closely controlled. The intermediate lighter vapors, 50 heavier than the desired pressure distillate, which are allowed to escape with the pressure distillate, in ordinary methods of operation, are refluxed and the reflux circulated through 55 a separate heater where it is heated to the cracking temperature and then returned to the pressure still from which the vapors escaped. The reflux from these lighter constituents thereby assists in maintaining the 60 concentration of pitch-like constituents produced during the progress of the cracking operation below the saturation point.

The oil employed for promoting and controlling the improved refluxing operation of 65 the present invention may be a part of the

pressure distillate from the same still or from other pressure stills operated to produce a similar distillate, or other blends or fractions including constituents corresponding in character to constituents of the desired distillate 70 may be employed. Where the operation is carried out with the introduction of additional fresh heavier charging stock, the oil employed for promoting and controlling the refluxing operation may also be introduced 75 into direct contact with the vapors from the still in admixture with all or a part of this additional fresh charging stock. Or, the oil employed for promoting and controlling the refluxing operation may be introduced near 80 the upper end of a reflux tower through which the vapors from the pressure still are passed upwardly and all or a part of the heavier charging stock introduced into the tower at some intermediate point. 85

As compared to ordinary methods of operation, the introduction into direct contact with the vapors in the reflux tower of an oil including a large amount of constituents corresponding to the constituents of the desired 90 pressure distillate and the consequent vaporization of the introduced oil and refluxing of the heavier intermediate constituents from the still may result, where the operation is carried out to produce a very light fraction, 95 in the consumption of an excessive amount of heat in revaporizing in a cyclic manner these intermediate constituents with a resulting decrease in the rate of cracking. This decrease in the rate of cracking may also be 100 accompanied by an inability on the part of the still to maintain, autogenously, the desired pressure due to the decreased rate of production of cracked vapors and fixed gases. In carrying out the process of the present invention, these conditions may be offset, if encountered, in any one of several ways. For 105 this purpose, the still pressure may be maintained by the introduction of an extraneous gas, or the still pressure may be reduced and regulated at a point between the still and the condenser. By operating the pressure still in either of these ways, the proper still pressure can be maintained although the rate of cracking may be somewhat decreased. An 110 increased still pressure, as compared to that employed in ordinary methods, may also be employed to prevent, to a greater or less extent, the revaporization of these intermediate constituents before they are further cracked. The 115 operation of the reflux tower may also be regulated so that the pressure distillate escaping includes a somewhat increased amount of the lighter of these intermediate constituents which tend to be recycled to an 120 excessive extent between the reflux tower and the still. 125

Where a circulatory pressure still is employed, in which the oil is circulated from and to a bulk supply tank through a heater 130

in which it is heated to the cracking temperature, the reflux from the refluxing operation may be introduced to the still in a manner such that it is directed through the heater with the circulating oil so that it also exerts a solvent action in the heater.

The refluxing operation of the present invention may, with particular advantage, be carried out in a heat insulated reflux tower 10 so that heat exchange is confined to the constituents in direct contact in the tower, thereby promoting heat economy, by preventing loss of heat to the air or other external cooling medium, permitting closer regulation 15 and control of the refluxing operation, and effecting a maximum fractionation of the vapors from the still.

While the refluxing operation of the present invention may be carried out in reflux towers of various types, it is carried out with particular advantage in a reflux tower of baffle construction having a relatively large area for free passage of the vapors therethrough. A tower of this type offers important advantages in safety and in ease of 25 control, is readily repaired, and has other advantages which will further appear.

The invention will be further described and illustrated in connection with the accompanying drawing which shows, in a somewhat diagrammatic and conventional manner, a pressure still adapted for the practice of the process of the invention; but it is intended and will be understood that the invention is not limited to the specific method of operation so described.

The accompanying drawing represents, in elevation and partly in section, a pressure still adapted for the practice of the process 40 of the invention. The drawing is not intended to be to scale, for example, the storage tanks illustrated may be materially larger in actual practice than is shown by the proportions of the drawing.

While the process of the invention may be carried out in pressure cracking stills of different types, it is of special value and application in connection with circulatory pressure stills of the character illustrated. This 50 pressure cracking still is of the general construction and operation described and illustrated in United States Letters Patent No. 1,285,200 granted to the Sinclair Refining Company November 19, 1918, on the application of Edward W. Isom.

The pressure still illustrated is made up of the bulk supply tank 5 located away from the heating furnace, the vertically arranged heating tubes 6 located in the heating flue 60 of the furnace, and circulating pipes 7, 8 and 9 connecting successively the bulk supply tank, a circulating pump 10, the lower end of the heating tubes, and the upper end of the heating tubes and the bulk supply tank. 65 A circulating pump may, with advantage,

be employed for circulating the oil from the bulk supply tank through the heating tubes and back to the bulk supply tank; or the circulating pump may be omitted and thermosyphonic action relied upon for maintaining circulation but with decreased still capacity. Arranged above the bulk supply tank is a reflux tower 11 having a series of baffles therein and connected with the vapor dome of the bulk supply tank through the vapor line 12. 70 The vapors from the top of the reflux tower escape through a vapor line 13 to a condenser 14 arranged to discharge into the receiver 15. From the receiver, the condensed distillate is discharged through valved connection 16 and the uncondensed vapors and gases through the valved connection 17. A connection 18 is provided at the lower part of the circulating connections of the still for pumping out and charging the still, and a tar draw-off connection for use during the operation of the still is provided at 19. A connection 20 is also arranged for introducing fresh charging stock into the circulating oil through the bearings of the circulating pump. Where no circulating pump is employed this connection may be arranged to discharge directly into the circulating connections of the still, advantageously in the connection for circulating oil from the bulk supply tank to the heating tubes. 85

The pressure may be regulated and reduced by means of a regulating valve 50 interposed between the reflux tower and the condenser, or the still pressure may be maintained 100 through the condenser and the pressure regulated and controlled by a suitable valve or valves arranged beyond the condenser. Where an extraneous gas is employed for maintaining the still pressure, the gas pressure may be applied through connection 17 and the still, condenser and receiver maintained in open communication. 105

A pump 21 is arranged to force oil through connection 32 to a spray-head 33 in the upper end of the reflux tower, and through it into direct contact with the vapors in the reflux tower. This pump is arranged to draw distillate from either the distillate tank 24, connected to the receiver through connection 16, or from any suitable source delivered through connection 34. The reflux tower is advantageously provided with a heat insulating jacket (not shown) of suitable material, such as asbestos or mineral wool; and the other 115 exposed parts of the pressure still may also with advantage be covered with heat insulating material to prevent unnecessary heat loss and to promote heat economy. A pump 28 is arranged to force additional fresh heavy 120 charging stock from the supply tank 35 into the pressure still through connection 20 and the bearings of the circulating pump 10, into the reflux tower at an intermediate point through the spray-head 36 and connection 130

37, or into the upper end of the reflux tower through connections 38 and 32. The heavier charging stock may be introduced into the still through one or more of these channels at the same time and valves 20', 37' and 38' are provided in the respective connections to control and regulate the distribution of the additional heavy charging stock.

An auxiliary heating coil 39 is shown as arranged in the heating flue of the furnace 10 between the firebox and the vertical heating tubes so that the auxiliary coil is subjected to the hottest heating gases and the main heating tubes to the tempered heating gases which have passed over the auxiliary coil. 15 This auxiliary coil is arranged so that the reflux from the reflux tower, either with or without the admixture of fresh charging stock, is circulated therethrough, thus subjecting the reflux to the hottest heating gases 20 and at the same time protecting the heating surfaces over which the pitch containing charge of oil in the still proper is circulated.

For this purpose an auxiliary tank or reservoir 40 is arranged to receive the reflux from the reflux tower through connection 41. This reservoir has a vent pipe 42 leading back to the reflux tower. A valved connection 43 is also provided for discharging reflux from 25 the reflux tower directly into the bulk supply tank 5. The reservoir 40 is also connected through the pipes 44 and 45 to the feed line of the auxiliary coil. A pump 46 is arranged to pump the oil from the reservoir 40 through 30 the auxiliary coil, while the connecting pipe 47 permits circulation by gravity and by convection when the pump 46 is not used. The pipe 48 leads from connection 44 to the bottom of the bulk supply tank for supplying 35 the auxiliary coil, while the connecting pipe 47 permits circulation by gravity and by convection when the pump 46 is not used. The pipe 48 leads from connection 44 to the bottom of the bulk supply tank for supplying 40 additional oil in case the amount of reflux is insufficient to maintain full the auxiliary coil. A connection 49 is also provided for circulating fresh charging stock through the auxiliary coil if desired. A connection 51 is 45 arranged between the inlet 45 of the auxiliary coil and the discharge side of the circulating pump 10, and may be used in starting a still in operation as well as draining the auxiliary coil and connection pipe when the still is 50 pumped out. The auxiliary coil 39 is arranged to discharge through connection 52 into the return circulating connection 9 to the bulk supply tank.

The auxiliary reservoir or tank 40 is shown 55 as located within the bulk supply tank 5, although there is not an open communication therewith except through the pipe connections. This location of the auxiliary reservoir is not essential but is convenient and 60 enables a tank construction to be used which does not need to withstand high pressure as the pressure inside and out is approximately the same.

In carrying out the cracking process of the 65 present invention in the apparatus illustrat-

ed in the drawing, the still is charged with fresh charging stock in the usual way, for example through connection 18, and brought to the cracking temperature and pressure in the usual manner. The charging stock, for example, may be gas oil or other suitable charging stock which is to be cracked for the production of gasoline or pressure distillate. The pressure maintained in the still during the cracking operation can vary, depending upon the character of the charging stock and other considerations. For example, with a gas oil charging stock and for the production of gasoline a pressure up to 125 lbs. per sq. inch or more can be used. After cracking 70 conditions of temperature and pressure are reached, cracking begins and takes place in a gradual and progressive manner, the vapors liberated in the still proper escaping and passing upwardly through the reflux tower. The reflux from the reflux tower, together with any unvaporized constituents of oil introduced directly thereto in liquid form, is circulated through the auxiliary heating coil 75 80 85 90 95 100 105 110 115 120 125 130 39 before it is returned to the main body of oil in the still and before it escapes from the pressure still as a vapor. The reflux is thus subjected to the cracking temperature, and, moreover, in the apparatus illustrated, is subjected to the hottest heating gases. During the preliminary heating operation, or at any time thereafter if the supply of reflux is for any reason insufficient to maintain full the auxiliary coil, oil other than reflux condensate may be supplied thereto either from the bulk supply tank through connection 48, from the circulating connection 51, or from an external supply through connection 49.

As soon as the pressure from the still has been brought up to the desired point and vapors are being taken off through the reflux tower, or shortly thereafter, the introduction through connection 32 of a fraction corresponding in character to the desired pressure distillate into the top of the tower in direct contact with the vapors therein is begun. For example, in the production of gasoline, a gasoline character fraction or an oil including gasoline constituents may be introduced into the top of the reflux tower in this manner. During the initial period of operation, a fraction from a separate source, for example distillate from a preceding run, supplied through connection 34, may be employed for introduction into the reflux tower; and during the latter period of operation, the fraction introduced into the reflux tower may be drawn from this same source or a part of the distillate produced by the still during the same operation may be so employed, or a mixture or blend of such distillates or fractions may be used. As the distillation proceeds, the still charge is maintained by the introduction of additional charging stock, for example gas oil, and before the pitch content of the

charge reaches the saturation point, the withdrawal of tar through connection 19 is begun and the rate of tar draw-off and of fresh charging stock feed is regulated to maintain the pitch content of the charge below the saturation point. The heavier charging stock may be introduced to the still through the bearings of the circulating pump or it may be introduced into the reflux tower at an intermediate point through connection 37 and lighter oil for controlling and regulating the refluxing operation introduced into the upper part of reflux tower so that the final separation between the heavier constituents and the constituents suitable as components of the desired pressure distillate is effected in the upper part of the tower above the point of introduction of the heavier feed oil.

The lighter oil introduced into the upper portion of the reflux tower when operating as above described is vaporized to a greater or less extent by heat exchange with the vapors from the still and the heavier constituents of the vapors are refluxed by the cooling effected by the vapors. The extent to which this refluxing oil is vaporized depends to a great extent upon the character of the refluxing oil; for example, using a gasoline feed in the production of a gasoline distillate the feed may be completely vaporized and escape and be condensed with the distillate. Since the constituents of this refluxing feed which are vaporized correspond in character to the desired distillate, heavier components are not introduced into the distillate by employing such a feed as a refluxing medium.

The apparatus illustrated in the drawing may also be operated in accordance with the process of the invention by introducing all or a part of the heavier charging stock introduced into the reflux tower, into the upper end of the tower in admixture with the lighter oil for controlling and regulating the refluxing operation, in which case the lighter constituents of the mixture will be vaporized in the reflux tower, promoting and controlling the refluxing operation in a manner similar to that which has been described. To the extent that the heavier charging stock is introduced into direct contact with the vapors in the reflux tower, it assists in promoting the refluxing operation and is thereby preheated. Somewhat more effective separation of the heavier constituents may be effected, however, by introducing the major part of the heavier charging stock introduced into the tower at an intermediate point and by introducing lighter oil for controlling and regulating the refluxing operation into the upper part of the tower.

The process of the invention may be carried out in the production of a 450° F. end point gasoline with a feed to the reflux tower comprising a major part of gasoline constituents boiling below 450° F. In such an opera-

tion the major part of the constituents of the vapors from the still boiling between about 450° F. and 500° F. and substantially all of the heavier vapors can be refluxed and returned through the auxiliary coil to the still, and, by proper regulation, a gasoline character fraction can be directly produced. The refluxing operation, however, may be regulated so that a pressure distillate including a larger amount of the heavier components is produced. For example, in carrying out the process of the invention for the production of a distillate containing about 85% of 450° F. end point gasoline, a gas oil character charging stock may be initially charged to the still, the still brought to a cracking pressure of about 125 lbs. per square inch and additional gas oil character stock supplied to the still and tar withdrawn therefrom during the cracking operation to maintain the still charge approximately constant. At the same time a distillate including about 50% of 450° F. end point gasoline may be introduced into the reflux tower to promote the refluxing operation, as above described.

In carrying out the process of the present invention for the production of a gasoline character distillate from a heavier hydrocarbon oil, a gasoline fraction or distillate which it is desired to blend with the pressure distillate may be employed as the refluxing agent and may be introduced into the reflux tower in direct contact with the hot vapors from the still for this purpose. For example, a straight run gasoline which it is desired to blend with the cracked gasoline may be introduced into the reflux tower in this way. The gasoline fraction introduced into the reflux tower is vaporized by heat exchange with the hot vapors therein and at the same time refluxes to the still the heavier constituents of the vapors. The gasoline fraction is thus employed to promote and control the refluxing operation while at the same time it escapes with the pressure distillate and is condensed therewith so that the blending operation is carried out in an improved manner.

Other advantages of the process of the invention are that the distillates produced thereby are relatively free from heavy or tarry constituents of the fresh oil or still charge and the amount of heavier constituents in the pressure distillate which may tend to carry with them objectionable impurities or otherwise interfere with the refining operations is reduced, further facilitating the refining treatment. The process of the present invention also enables the production of an increased amount of gasoline, or the desired pressure distillate, due in part to the better fractionation effected in the reflux tower on the pressure still and in part to a reduction in the overcracking of gasoline constituents condensed during the refluxing operation and subjected to further cracking treatment.

One evidence indicating a decrease in over-cracking of constituents suitable as components of the desired distillate is a decrease in the production of fixed gas. Thus, the amount of fixed gas for one hundred gallons of charge may be reduced to 18 to 20 pounds as compared to 21 to 22 pounds in the ordinary method of operation. Another important advantage of the invention is that it enables the production of an increased yield of gasoline or pressure distillate on the oil charged to the still. As compared to ordinary methods of operation in which constituents which might be further cracked to produce additional gasoline escape with the distillate and which gasoline constituents are refluxed and overcracked the yield of gasoline and gas oil charged to the still may be increased from 2 to 6% or more. An important economy may also be effected in the amount of cooling water, or of other cooling medium, required for cooling and condensing the pressure distillate due to the concentration of the pressure distillate, and the size of the condenser employed may be correspondingly reduced.

Other advantages of the process of the invention are that it assists in making possible a material saving in fuel and affords maximum ease and control and simplicity of operation when applied to the direct production of a gasoline character distillate.

I claim:

1. An improved method of cracking hydrocarbon oils, which comprises heating a body of the oil to a cracking temperature under pressure in a pressure still by circulation over externally heated surfaces, subjecting the vapors from the still to a refluxing operation in direct contact with a distillate including constituents corresponding in character to the desired distillate, positively circulating the reflux from the refluxing operation through a heater and separately heating it to the cracking temperature therein and then introducing it into the main body of oil being heated in the still.

2. An improved method of cracking hydrocarbon oils for the production of a gasoline-line-character distillate, which comprises heating a body of the oil to a cracking temperature under pressure in a pressure still by circulation over externally heated surfaces, subjecting the vapors from the still to a refluxing operation in direct contact with a distillate including gasoline-character constituents, positively circulating the reflux from the refluxing operation through a heater and separately heating it to the cracking temperature therein and then introducing it into the main body of oil being heated in the still.

3. An improved method of cracking hydrocarbon oils, which comprises circulating a body of the oil from and to a bulk supply

tank through a heater while under pressure, heating the oil to a cracking temperature in the heater, subjecting the vapors formed to a refluxing operation in direct contact with a distillate including constituents corresponding in character to the desired distillate, positively circulating the reflux from the refluxing operation through a separate heater and separately heating it to the cracking temperature therein and then introducing it into the circulating body of oil.

4. An improved method of cracking hydrocarbon oils, which comprises heating a body of the oil to a cracking temperature under pressure in a pressure still by circulation over externally heated surfaces, subjecting the vapors from the still to a refluxing operation, subjecting the vapors from the refluxing operation to a condensing operation to produce a distillate, withdrawing pitch-laden oil from and introducing additional fresh oil into the body of oil in the still during the progress of the cracking operation, independently introducing a distillate including a substantial quantity of constituents corresponding in character to constituents of the distillate produced from the vapors from the refluxing operation into direct contact with the vapors in the refluxing operation, positively circulating the reflux from the refluxing operation through a heater and separately heating it to the cracking temperature therein and then introducing it into the main body of oil being heated in the still.

5. An improved method of cracking hydrocarbon oils, which comprises heating a body of the oil to a cracking temperature under pressure in a cracking still by circulation over externally heated surfaces, passing the vapors from the still upwardly through a reflux tower, passing uncondensed vapors from the reflux tower to a condenser to produce a distillate, introducing a distillate including constituents corresponding in character to the desired distillate into the upper end of the reflux tower in direct contact with the vapors therein, introducing additional fresh oil into the reflux tower at an intermediate point, positively circulating the reflux from the refluxing operation through a heater and separately heating it to the cracking temperature therein and then introducing it into the main body of oil being heated in the still.

In testimony whereof, I have subscribed my name.

EUGENE C. HERTHEL.
